(57) **ABSTRACT**

A developing device includes a developing roller, a developing case, and a support. The developing roller includes a sleeve and a magnetic field generator. The sleeve is rotatable and includes a hollow shaft at an axial end of the sleeve. The magnetic field generator is irrationally disposed inside the sleeve and includes a non-rotating shaft at an axial end of the magnetic field generator. The non-rotating shaft penetrates through the hollow shaft and projects outward. The developing case is configured to store developer and rotatably supports the hollow shaft. The support includes a fitting portion into which the non-rotating shaft of the magnetic field generator is irrationally fitted. The support is supported on the developing case using the fitting portion as a main-positioning portion.

DEVELOPING DEVICE AND IMAGE FORMING APPARATUS INCORPORATING SAME

CROSS-REFERENCE TO RELATED APPLICATION

This patent application is based on and claims priority pursuant to 35 U.S.C. § 119(a) to Japanese Patent Application No. 2020-152727, filed on Sep. 11, 2020 in the Japan Patent Office, the entire disclosure of each of which is hereby incorporated by reference herein.

BACKGROUND

Technical Field

This disclosure generally relates to a developing device to develop a latent image formed on a surface of an image bearer such as a photoconductor drum, and an image forming apparatus including the developing device, such as a copier, a printer, a facsimile machine, or a multifunction peripheral (MFP) having at least two of such functions.

Related Art

As a developing device included in an image forming apparatus such as a copier and a printer, a developing device employing a two-component developing method is widely used that includes a developing roller in which a magnetic field generator such as a magnet is disposed.

SUMMARY

This specification describes an improved developing device that includes a developing roller, a developing case, and a support. The developing roller includes a sleeve and a magnetic field generator. The sleeve is rotatable and includes a hollow shaft at an axial end of the sleeve. The magnetic field generator is irrotationally disposed inside the sleeve and includes a non-rotating shaft at an axial end of the magnetic field generator. The non-rotating shaft penetrates through the hollow shaft and projects outward. The developing case is configured to store developer and rotatably supports the hollow shaft. The support includes a fitting portion into which the non-rotating shaft of the magnetic field generator is irrotationally fitted. The support is supported on the developing case using the fitting portion as a main-positioning portion.

BRIEF DESCRIPTION OF THE DRAWINGS

A more complete appreciation of the disclosure and many of the attendant advantages thereof will be readily obtained as the same becomes better understood by reference to the following detailed description when considered in connection with the accompanying drawings, wherein:

FIG. 1 is a schematic view of a configuration of an image forming apparatus according to an embodiment of the present disclosure;

FIG. 2 is a cross-sectional view of an image forming unit of the image forming apparatus of FIG. 1;

FIG. 3 is a schematic cross-sectional view of a developing device and a photoconductor drum of the image forming unit of FIG. 2 as viewed along a longitudinal direction of the developing device;

2

FIG. 4 is a schematic enlarged view of an end portion of the developing device of FIG. 3 in an axial direction of a developing roller;

FIG. 5 is a schematic enlarged view of the end portion of the developing device, a support, and a gear holder when the support and the gear holder are removed from the developing device of FIG. 4;

FIG. 6 is a schematic view of the gear holder of FIG. 5 viewed from a direction A in FIG. 5;

FIG. 7A is a schematic view of the support of FIG. 5 viewed from the direction A in FIG. 5;

FIG. 7B is a schematic view of the support of FIG. 5 viewed from a direction B in FIG. 5;

FIG. 8A is a schematic enlarged view of an end portion of the developing device according to a comparative embodiment in the axial direction of a developing roller;

FIG. 8B is a schematic view of a support of the developing device according to the comparative embodiment of FIG. 8A;

FIG. 9A is a schematic view of the support according to a first variation viewed from the direction A of FIG. 5;

FIG. 9B is a schematic view of the support according to the first variation viewed from the direction B of FIG. 5;

FIG. 10A is a schematic view of the support according to a second variation viewed from the direction A of FIG. 5;

FIG. 10B is a schematic view of the support according to the second variation viewed from the direction B of FIG. 5;

FIGS. 11A and 11B are schematic views of the support according to a third variation;

FIG. 12 is an enlarged view of the support and a D-cut portion of a non-rotating shaft, illustrating a positional relationship of the support and the D-cut portion in the axial direction of the shaft; and

FIGS. 13A and 13B are schematic views of the support according to a fourth variation.

The accompanying drawings are intended to depict embodiments of the present disclosure and should not be interpreted to limit the scope thereof. The accompanying drawings are not to be considered as drawn to scale unless explicitly noted. Also, identical or similar reference numerals designate identical or similar components throughout the several views.

DETAILED DESCRIPTION

In describing embodiments illustrated in the drawings, specific terminology is employed for the sake of clarity. However, the disclosure of this patent specification is not intended to be limited to the specific terminology so selected and it is to be understood that each specific element includes all technical equivalents that operate in a similar manner and achieve similar results.

Referring now to the drawings, embodiments of the present disclosure are described below. As used herein, the singular forms "a," "an," and "the" are intended to include the plural forms as well, unless the context clearly indicates otherwise. Identical reference numerals are assigned to identical components or equivalents and a description of those components is simplified or omitted.

Initially with reference to FIG. 1, a configuration and operation of an image forming apparatus 1 according to an embodiment of the present disclosure is described below.

The image forming apparatus 1 according to the present embodiment is a tandem multicolor image forming apparatus in which process cartridges 20Y, 20M, 20C, and 20BK are arranged in parallel to each other, facing an intermediate transfer belt 40. In each of the process cartridges 20Y, 20M,

20C, and 20BK, a developing device 26 is disposed to face a photoconductor drum 21 as illustrated in FIG. 2.

In FIG. 1, the image forming apparatus 1, which is a color copier in the present embodiment, includes a document conveyance device 2, a scanner 3 as a document reading device, and an exposure device 4 as a writing device. The document conveyance device 2 conveys a document to the scanner 3. The scanner 3 reads image data of the document.

The exposure device 4 emits a laser beam based on input image data.

In addition, the image forming apparatus 1 includes the process cartridges 20Y, 20M, 20C, and 20BK to form yellow, magenta, cyan and black toner images on respective surfaces of the photoconductor drums, respectively, and an intermediate transfer belt 40 on which the yellow, magenta, cyan and black toner images are transferred and superimposed.

The image forming apparatus 1 further includes a sheet feeder 61 to accommodate sheets P such as paper sheets, a secondary transfer roller 65 to transfer the toner image formed on the intermediate transfer belt 40 onto the sheet P, a fixing device 66 to fix the unfixed toner image on the sheet P, and toner containers 70 to supply toners of respective colors to the developing devices 26 of the corresponding process cartridges 20Y, 20M, 20C, and 20BK.

Each of the process cartridges 20Y, 20M, 20C, and 20BK includes the photoconductor drum 21 as an image bearer, a charging device 22, and a cleaning device 23, which are united as a single unit as illustrated in FIG. 2. Each of the process cartridges 20Y, 20M, 20C, and 20BK, which is expendable, is replaced with a new one when depleted in a body of the image forming apparatus 1.

In each of the process cartridges 20Y, 20M, 20C, and 20BK, the developing device 26 is disposed to face the photoconductor drum 21. The developing device 26 is expendable and replaced with a new one when depleted in the body of the image forming apparatus 1. An operator can independently perform an installation and removal operation of the developing device 26 with respect to the body of the image forming apparatus 1 and an installation and removal operation of the process cartridges 20Y, 20M, 20C, and 20BK with respect to the body of the image forming apparatus 1 as different operations.

In the process cartridges 20Y, 20M, 20C, and 20BK, yellow, magenta, cyan, and black toner images are formed on the respective photoconductor drums 21 as the image bearers.

A description is provided of image forming processes of the image forming apparatus 1 to form a color toner image on a recording medium.

A conveyance roller of the document conveyance device 2 conveys a document on a document table onto a platen (exposure glass) of the scanner 3. The scanner 3 optically scans image data for the document on the platen.

The yellow, magenta, cyan, and black image data are transmitted to the exposure device 4. The exposure device 4 irradiates the photoconductor drums 21 (see FIG. 2) of the corresponding process cartridges 20Y, 20M, 20C, and 20BK with laser beams (as exposure light) L based on the yellow, magenta, cyan, and black image data, respectively.

Each of the four photoconductor drums 21 rotates clockwise in FIGS. 1 and 2. The surface of the photoconductor drum 21 is uniformly charged at a position where the photoconductor drum 21 faces the charging device 22 that is a charging roller, which is referred to as a charging process. Thus, the surface of the photoconductor drum 21 is charged to a certain potential. When the charged surface of the

photoconductor drum 21 reaches a position to receive the laser beam L emitted from the exposure device 4, an electrostatic latent image based on the image data is formed on the surface of the photoconductor drum 21, which is referred to as an exposure process.

The laser beam L corresponding to the yellow image data is directed to the surface of photoconductor drum 21 in the process cartridge 20Y, which is the first from the left in FIG. 1 among the four process cartridges 20Y, 20M, 20C, and 20BK. A polygon mirror that rotates at high velocity deflects the laser beam L for yellow along the rotation axis direction of the photoconductor drum 21 (i.e., the main-scanning direction) so that the laser beam L scans the surface of the photoconductor drum 21. Thus, an electrostatic latent image for yellow is formed on the surface of the photoconductor drum 21 charged by the charging device 22.

Similarly, the laser beam L corresponding to the cyan image data is directed to the surface of the photoconductor drum 21 in the second process cartridge 20C from the left in FIG. 1, thus forming an electrostatic latent image for cyan on the surface of the photoconductor drum 21. The laser beam L corresponding to the magenta image data is directed to the surface of the photoconductor drum 21 in the third process cartridge 20M from the left in FIG. 1, thus forming an electrostatic latent image for magenta on the photoconductor drum 21. The laser beam L corresponding to the black image data is directed to the surface of the photoconductor drum 21 in the fourth process cartridge 20BK from the left in FIG. 1, thus forming an electrostatic latent image for black on the photoconductor drum 21.

Then, the surfaces of the photoconductor drums 21 having the respective electrostatic latent images reach positions opposed to the corresponding developing devices 26 (see FIG. 2). The developing device 26 deposits toner of each color onto the surface of the photoconductor drum 21 and develops the electrostatic latent image on the photoconductor drum 21 into a toner image, which is referred to as a development process.

After the development process, the surfaces of the photoconductor drums 21 reach positions facing the intermediate transfer belt 40. The primary transfer rollers 24 are disposed at the positions where the photoconductor drums 21 face the intermediate transfer belt 40 and in contact with an inner circumferential surface of the intermediate transfer belt 40, respectively. At the positions of the primary transfer rollers 24, the toner images on the photoconductor drums 21 are sequentially transferred to and superimposed on the intermediate transfer belt 40, forming a multicolor toner image thereon, which is referred to as a primary transfer process.

After the primary transfer process, the surface of the photoconductor drum 21 reaches a position opposite the cleaning device 23. The cleaning device 23 collects untransferred toner remaining on the photoconductor drum 21, which is referred to as a cleaning process.

Subsequently, a residual potential of the surface of the photoconductor drum 21 is removed at a position opposite the discharger, and a series of image forming processes performed on the photoconductor drum 21 is completed.

Meanwhile, the surface of the intermediate transfer belt 40, onto which the single-color toner images on the photoconductor drums 21 are superimposed, moves in the direction indicated by arrow in FIG. 1 and reaches a position opposite the secondary transfer roller 65. The secondary transfer roller 65 secondarily transfers the multicolor toner image on the intermediate transfer belt 40 to the sheet P, which is referred to as a secondary transfer process.

After the secondary transfer process, the surface of the intermediate transfer belt 40 reaches a position opposite a belt cleaning device. The belt cleaning device collects untransferred toner on the intermediate transfer belt 40 to complete a series of transfer processes on the intermediate transfer belt 40.

The sheet P is conveyed from the sheet feeder 61 to the position of the secondary transfer roller 65 via a registration roller pair 64.

Specifically, a sheet feed roller 62 feeds the sheet P from top of multiple sheets P accommodated in the sheet feeder 61, and the sheet P is conveyed to a registration roller pair 64 through a sheet feed path. The sheet P that has reached the registration roller pair 64 is conveyed toward the position of the secondary transfer roller 65, timed to coincide with the arrival of the multicolor toner image on the intermediate transfer belt 40.

Subsequently, the sheet P, onto which the multicolor image is transferred, is conveyed to the fixing device 66. The fixing device 66 includes a fixing roller and a pressure roller pressing against each other. In a nip between the fixing roller and the pressure roller, the multicolor image is fixed on the sheet P.

After the fixing process, an output roller pair 69 ejects the sheet P as an output image to the exterior of the image forming apparatus 1, and the ejected sheet P is stacked on an output tray 5 to complete a series of image forming processes.

Next, with reference to FIGS. 2 and 3, the image forming units of the image forming apparatus 1 are described in detail below.

The four image forming units in the body of the image forming apparatus 1 have a similar configuration except the color of the toner used in the image forming processes. Therefore, parts of the image forming unit such as the process cartridge and the developing device are illustrated without suffixes Y, M, C, and BK, which denote the color of the toner, in the drawings.

As illustrated in FIG. 2, the process cartridge 20 mainly includes the photoconductor drum 21 as the image bearer, the charging device 22, and the cleaning device 23, which are stored in a case of the process cartridge 20 as a single unit.

The photoconductor drum 21 is an organic photoconductor designed to be charged with a negative polarity and includes a photosensitive layer formed on a drum-shaped conductive support.

The charging device 22 is the charging roller including a conductive core and an elastic layer of moderate resistivity coated on the conductive core. A power supply applies a predetermined voltage to the charging device 22 that is the charging roller, and the charging device 22 uniformly charges the surface of the photoconductor drum 21 opposite the charging device 22.

The cleaning device 23 includes a cleaning blade 23a and a cleaning roller 23b that contact the photoconductor drum 21. For example, the cleaning blade 23a is made of rubber, such as urethane rubber, and contacts the surface of the photoconductor drum 21 at a predetermined angle with a predetermined pressure. The cleaning roller 23b is a brush roller in which brush bristles are provided around a core.

As illustrated in FIGS. 2 and 3, the developing device 26 mainly includes a developing roller 26a as a developer bearer, a first conveying screw 26b1 as a first conveyor facing the developing roller 26a, a partition 26e, a second conveying screw 26b2 as a second conveyor facing the first conveying screw 26b1 via the partition 26e, and a doctor

blade 26c as a developer regulator facing the developing roller 26a to regulate an amount of developer borne on the developing roller 26a.

The developing device 26 stores a two-component developer including carrier and toner.

The developing roller 26a is opposed to the photoconductor drum 21 with a small gap, thereby forming a developing range. As illustrated in FIG. 3, the developing roller 26a includes stationary magnets 26a1 as magnetic field generators, which are fixed not to rotate, inside and a sleeve 26a2 that rotates around the magnets 26a1. The magnets 26a1 generate multiple poles (magnetic fields) around the outer circumferential surface of the developing roller 26a.

The doctor blade 26c is above the developing roller 26a and is opposed to the developing roller 26a with a small gap as a doctor-gap DG to suitably adjust the amount of the developer carried on the developing roller 26a.

The first conveying screw 26b1 and the second conveying screw 26b2 convey the developer stored in the developing device 26 in the longitudinal direction of the developing device 26, thereby establishing a circulation path indicated by the dashed arrow in FIG. 3. That is, the first conveying screw 26b1 establishes a first conveyance path B1, and the second conveying screw 26b2 establishes a second conveyance path B2. The circulation path of the developer includes the first conveyance path B1 and the second conveyance path B2.

The partition 26e is an inner wall and separates the first conveyance path B1 from the second conveyance path B2, and the first and second conveyance paths B1 and B2 communicate with each other via first and second communication openings 26f and 26g disposed at both ends of the first and second conveyance paths B1 and B2 in the longitudinal direction. Specifically, with reference to FIG. 3, in a conveyance direction of the developer, an upstream end of the first conveyance path B1 communicates with a downstream end of the second conveyance path B2 via the first communication opening 26f. Additionally, in the conveyance direction of the developer, a downstream end of the first conveyance path B1 communicates with an upstream end of the second conveyance path B2 via the second communication opening 26g. That is, the partition 26e is disposed along the circulation path in the longitudinal direction except both ends of the circulation path.

The first conveying screw 26b1 in the first conveyance path B1 is opposite the developing roller 26a, and the second conveying screw 26b2 in the second conveyance path B2 is opposite the first conveying screw 26b1 in the first conveyance path B1 via the partition 26e. The first conveying screw 26b1 supplies developer to the developing roller 26a and collects the developer that separates from the developing roller 26a after the development process while conveying the developer in the longitudinal direction of the developing device 26 (that is the lateral direction in FIG. 3 and an axial direction of the first conveying screw). The second conveying screw 26b2 stirs and mixes the developer after the development process conveyed from the first conveyance path B1 with a fresh toner supplied from a replenishing port 26d while conveying the developer in the longitudinal direction of the developing device 26.

In the present embodiment, the first and second conveying screws 26b1 and 26b2 are horizontally arranged in parallel. Each of the first and second conveying screws 26b1 and 26b2 includes a shaft and a screw blade wound around the shaft.

A further detailed description is given of the image forming processes described above, focusing on the development process.

The developing roller 26a as the developer bearer rotates clockwise in a direction indicated by arrow in FIG. 2. As illustrated in FIGS. 2 and 3, the first conveying screw 26b1 and the second conveying screw 26b2 are disposed facing each other with the partition 26e interposed therebetween and rotate in directions indicated by arrows in FIGS. 2 and 3. Toner is supplied from the toner container 70 to the replenishing port 26d via a toner supply path. As the first conveying screw 26b1 and the second conveying screw 26b2 rotate in the respective directions in FIG. 2, the developer stored in the developing device 26 circulates in the longitudinal direction of the developing device 26, that is, the direction indicated by the dashed arrow in FIG. 3, and the supplied toner is stirred and mixed with the developer circulating.

Stirring the developer causes the toner to be charged by friction with carrier in the developer and electrostatically attracted to the carrier. A magnetic force is generated on the developing roller 26a to scoop up the carrier. The magnetic force that is called as a developer scooping pole scoop up the carrier with the toner on the developing roller 26a. The developer borne on the developing roller 26a is conveyed in the counterclockwise direction indicated by arrow in FIG. 2 to a position opposite the doctor blade 26c. The doctor blade 26c adjusts an amount of the developer on the developing roller 26a at the position. Subsequently, rotation of the sleeve 26a2 conveys the developer to a developing range in which the developing roller 26a faces the photoconductor drum 21. The electric field formed in the developing range deposits toner on the electrostatic latent image formed on the photoconductor drum 21. As the sleeve 26a2 rotates, the developer remaining on the developing roller 26a reaches above the first conveyance path B1 and separates from the developing roller 23a. In the developing range, a predetermined voltage as a developing bias is applied to the developing roller 26a by a development power supply, and a surface potential as a latent image potential is formed on the photoconductor drum 21 in the charging process and the exposure process. The developing bias and the latent image potential form an electric field in the developing range.

In the present embodiment, the developing roller 26a and the photoconductor drum 21 do not move in the same direction in the developing range. The developing roller 26a moves in the opposite direction (counter direction) of the movement direction of the photoconductor drum 21 in the developing range. This configuration can satisfactorily develop the latent image on the photoconductor drum 21 even if the linear velocity difference between the photoconductor drum 21 and the developing roller 26a in the developing range is small.

The toner in the toner container 70 is supplied through the replenishing port 26d to the developing device 26 as the toner in the developing device 26 is consumed. The toner consumption in the developing device 26 is detected by a toner concentration sensor that magnetically detects a toner concentration in the developer (i.e., a ratio of toner to the developer) in the developing device 26.

The replenishing port 26d is disposed above an end of the second conveying screw 26b2 in the second conveyance path B2 in the longitudinal direction that is the left and right direction in FIG. 3.

The configuration and operation of the developing device 26 according to the present embodiment are described in further detail below.

As described above with reference to FIGS. 2 and 3, the developing device 26 includes a developing roller 26a as the developer bearer facing the photoconductor drum 21 and develops the latent image formed on the surface of the photoconductor drum 21 as the image bearer.

The developing roller 26a includes a sleeve 26a2 that is rotatable and magnets 26a1 as the magnetic field generator that is irrotationally fixed inside the sleeve 26a2. The sleeve 26a2 is a cylindrical member and has hollow shafts 26a20 at both ends in an axial direction of the sleeve 26a2 that is the lateral direction in FIG. 3. The magnets 26a1 is a columnar member and has non-rotating shafts 26a10 at both ends in an axial direction of the magnets 26a1 that is the lateral direction in FIG. 3.

A developing case 26k is a housing to store the developer inside, rotatably supports the developing roller 26a, the first conveying screw 26b1, and the second conveying screw 26b2, and holds the doctor blade 26c.

In particular, in the present embodiment, the developing case 26k rotatably supports the hollow shafts 26a20 formed at the axial ends of the sleeve 26a2 via ball bearings.

In addition, as illustrated in FIGS. 3 and 4, bearings 26r as gap forming members are disposed on the hollow shafts 26a20 of the sleeve 26a2 to contact the photoconductor drum 21. The bearings 26r set a gap between the photoconductor drum 21 and the developing roller 26a that is a development gap PG illustrated in FIG. 2.

Specifically, the bearings 26r are disposed at the hollow shafts 26a20 at both ends of the developing roller 26a and contact non-image formation areas of the surface of the photoconductor drum 21. The outer circumferential surfaces of the bearings 26r are made of low friction material. Abutting the bearings 26r against the surface of the photoconductor drum 21 determines a distance between the center axis of the developing roller 26a and the surface of the photoconductor drum 21 to set the development gap to a target value.

Accurately setting the development gap PG to the target value optimizes the electric field formed in the developing range, which enables suitably performing the development process.

Preferably, a biasing member is disposed to bias the developing device 26 toward the photoconductor drum 21 so that the bearings 26r reliably contact the photoconductor drum 21.

The developing case 26k holds the doctor blade 26c so as to be able to adjust the doctor gap DG that is a gap between the developing roller 26a and the doctor blade 26c (see FIG. 2).

When the doctor gap DG is accurately set to a target value, the doctor blade 26c optimizes an amount of the developer borne on the developing roller 26a that is supplied to the developing range in the development process, which enables suitably performing the development process.

As illustrated in FIGS. 4 to 7B, the developing device 26 according to the present embodiment includes supports 26m and gear holders 26n at both ends in the axial direction of the sleeve 26a2 that is the lateral direction in FIGS. 3 to 5 and a direction perpendicular to a plane on which FIGS. 6 and 7 are illustrated.

In addition, the developing device 26 includes the non-rotating shafts 26a10 at both ends of the magnets 26a1 as the magnetic field generator disposed inside the developing roller 26a. The non-rotating shaft 26a10 penetrates through the hollow shaft 26a20 of the sleeve 26a2 and projects outward, that is, right side in FIG. 4. As illustrated in FIG. 5, the non-rotating shaft 26a10 has a D-cut portion 26a11 on

a part of the non-rotating shaft **26a10** that is a predetermined area extending from the axial end toward the center. The D-cut portion **26a11** is made by a milling process so as to form a planar portion on the non-rotating shaft **26a10**, that is, so that a cross section of the D-cut portion **26a11** orthogonal to the axial direction has a D-shape.

The support **26m** has a D-shaped hole **26m20** (see FIGS. 7A and 7B) as a fitting portion into which the non-rotating shaft **26a10** of the magnets **26a1** as the magnetic field generator is fitted so as not to rotate.

The support **26m** is supported by the developing case **26k**, and the D-shaped hole **26m20** (the fitting portion) becomes a main-positioning portion.

Specifically, the support **26m** includes a base plate **26m1** as a main support and an electrode **26m2** as a conductor fixed on the base plate **26m1**. The base plate **26m1** is made of a non-conductive material such as resin. The electrode **26m2** is a plate made of a conductive material such as metal to apply a developing bias to the developing roller **26a** via the non-rotating shaft **26a10**.

As illustrated in FIGS. 7A and 7B, the base plate **26m1** as the main support has a hole **26m11** having a hole diameter larger than a shaft diameter of the non-rotating shaft **26a10**. The non-rotating shaft **26a10** passes through the hole **26m11** without contacting the base plate **26m1**.

In addition, the base plate **26m1** has a notch **26m13**. The developing case **26k** includes a boss **26k1** (see FIGS. 4 and 5) including a small diameter portion formed at the tip of the boss **26k1**. The small diameter portion is fitted into the notch **26m13**. The notch **26m13** serves as a sub-positioning portion when the support **26m** is disposed and positioned on the developing case **26k**.

Additionally, the base plate **26m1** has two holes **26m12** to fix the support **26m** with screws **90** (that is, screw fastening). The support **26m** is positioned on the developing case **26k** by using the D-shaped hole **26m20** serving as the main positioning portion and the notch **26m13** serving as the sub-positioning portion. The hole diameter of the holes **26m12** is sufficiently larger than the outer diameter of the external threads of the screw **90**.

On the other hand, as illustrated in FIGS. 7A and 7B, the electrode **26m2** as the conductor has a D-shaped hole **26m20** as a fitting portion into which the D-cut portion **26a11** of the non-rotating shaft **26a10** is fitted. The D-shaped hole **26m20** serves as the main-positioning portion when the support **26m** is fixed on the developing case **26k** as described above. As illustrated in FIG. 7A, the D-shaped hole **26m20** of the electrode **26m2** is exposed from the hole **26m11** of the base plate **26m1** when viewed from the inside of the developing device **26**, that is, viewed from the direction A in FIG. 5.

In addition, as illustrated in FIG. 7B, the electrode **26m2** has a thermal caulking hole **26m23** serving as the main-positioning portion and a thermal caulking slot **26m24** serving as the sub-positioning portion. Bosses formed on the base plate **26m1** pass through the thermal caulking hole **26m23** and thermal caulking slot **26m24** and are thermally melted, respectively, which is thermal caulking processing, to fix the electrode **26m2** on the base plate **26m1**.

The electrode **26m2** comes in contact with or separates from a terminal disposed in the body to the image forming apparatus **1** in conjunction with the attachment/detachment operation of the developing device **26** with respect to the main body of the image forming apparatus **1**. When the electrode **26m2** comes in contact with the terminal, a power supply in the body of the image forming apparatus **1** supplies

a predetermined developing bias to the developing roller **26a** via the terminal, the electrode **26m2**, and the non-rotating shaft **26a10**.

The electrode **26m2** has a cut-and-bent portion **26m21** (see FIGS. 4 and 7B) in the vicinity of the D-shaped hole **26m20** in order to ensure contact with the non-rotating shaft **26a10**. The cut-and-bent portion **26m21** prevents failure in applying the developing bias from the electrode **26m2** to the non-rotating shaft **26a10**.

Referring to FIGS. 4 to 6, the gear holder **26n** includes a support shaft **26n5** and an idler gear **26y** rotatably held by the support shaft **26n5**. The idler gear **26y** meshes with a drive gear **26x** disposed on the hollow shaft **26a20** and rotating together with the sleeve **26a2**. In the present embodiment, the gear holder **26n** is a bracket made of metal.

The drive gear **26x** disposed on the developing roller **26a** (specifically, the hollow shaft **26a20** of the sleeve **26a2**) meshes with or separates from a motor gear of a drive motor disposed in the body to the image forming apparatus **1** in conjunction with the attachment/detachment operation of the developing device **26** with respect to the main body of the image forming apparatus **1**. The drive motor drives the drive gear **26x** to drive and rotate the developing roller **26a**, and the driving force of the drive motor is transmitted to the gear train including the idler gear **26y** to drive the first conveying screw **26b1** and second conveying screw **26b2**.

The developing case **26k** supports the gear holder **26n** together with the support **26m**.

Specifically, the support shaft **26n5** of the gear holder **26n** is fitted into a depression formed in the tip of the boss **26k2** disposed on the developing case **26k** (see FIGS. 4 and 5). The support shaft **26n5** serves as the main-positioning portion when the gear holder **26n** is disposed and positioned on the developing case **26k**.

In addition, as illustrated in FIG. 6, the gear holder **26n** has a notch **26n3**. The small diameter portion formed at the tip of the boss **26k1** (see FIGS. 4 and 5) on the developing case **26k** is fitted into the notch **26n3**. The notch **26n3** serves as the sub-positioning portion when the gear holder **26n** is disposed and positioned on the developing case **26k**.

Additionally, the gear holder **26n** has two holes **26n2** to fix the gear holder **26n** on the developing case **26k** with screws **90** (that is, screw fastening). The gear holder **26n** is positioned on the developing case **26k** by using the support shaft **26n5** serving as the main positioning portion and the notch **26n3** serving as the sub-positioning portion. The hole diameter of the holes **26n2** is sufficiently larger than the outer diameter of the external threads of the screw **90**. The screws **90** to fix the gear holder **26n** on the developing case **26k** are used together with the screw fastening to fix the support **26m** on the developing case **26k**. In other words, the gear holder **26n** is sandwiched between the support **26m** and the developing case **26k**, and the gear holder **26n** and the support **26m** are screwed together on the developing case **26k**. (The gear holder **26n** and the support **26m** are assembled from the state illustrated in FIG. 5 to the state as illustrated in FIG. 4.)

As described above, the developing device **26** according to the present embodiment has a configuration in which the non-rotating shaft **26a10** of the magnets **26a1** is fitted into the D-shaped hole **26m20** serving as the main-positioning portion to support the support **26m** on the developing case **26k**.

The above-described configuration can more accurately and stably position the developing roller **26a** than a con-

figuration in which another part serves as the main-positioning portion to support the support **26m** on the developing case **26k**.

With reference to FIGS. 8A and 8B, a developing device **126** according to a comparative embodiment is described below. The developing device **126** includes a support **126m** including a boss **126m1** as the main-positioning portion at a position away from the developing roller **26a**. The developing device **126** includes a boss **126k2** disposed on the developing case **26k** and having a recess at the top of the boss **126k2**. The boss **126m1** as the main-positioning portion is fitted into the recess to support the support **126m** on the developing case **26k**. In the above-described configuration, accumulated tolerance of dimensions of parts and errors during assembling are likely to shift the position of the developing roller **26a** from a target position.

The hollow shaft **26a20** of the developing roller **26a** is supported on the developing case **26k** through a ball bearing, but the non-rotating shaft **26a10** of the developing roller **26a** is supported by the support **126m**. Accordingly, the non-rotating shaft **26a10** displaced from a target position with respect to the developing case **26k** generates force that bends the developing roller **26a** in a direction perpendicular to the axial direction of the developing roller **26a**. Driving force transmission from the drive gear **26x** disposed on the hollow shaft **26a20** to the idler gear **26y** disposed on the gear holder **126n** generates a reaction force acting on the drive gear **26x** so as to bend the developing roller **26a** in the direction perpendicular to the axial direction.

Accordingly, positions of the developing rollers **26a** (that is, the non-rotating shafts **26a10**) vary in the developing devices **126** according to the comparative embodiment (or each time the support **126m** is attached to the developing case **26k**) and frequently shift from the target position. Variation in the positions of the developing rollers **26a** causes variation in developing gaps PG between developing rollers **26a** and the photoconductor drums **21** and variation in doctor gaps DG between developing rollers **26a** and the doctor blades **26c**, which causes formation of an image having a large image density difference.

In contrast, the developing device **26** according to the present embodiment has the configuration in which the non-rotating shaft **26a10** of the developing roller **26a** is fitted into the D-shaped hole **26m20** serving as the main-positioning portion to fix the support **26m** on the developing case **26k**. This configuration easily positions the non-rotating shaft **26a10** to the target position with respect to the developing case **26k**. As a result, the above-described configuration is not likely to cause the disadvantage that accumulated tolerance of dimensions of parts and errors during assembling shift the position of the developing roller **26a** (that is, the non-rotating shaft **26a10**) from a target position and causes bending of the developing roller **26a** in the direction perpendicular to the axial direction. In the above-described configuration, the developing roller **26a** is not easily bent even when the driving force transmission from the drive gear **26x** disposed on the hollow shaft **26a20** to the idler gear **26y** disposed on the gear holder **126n** generates the reaction force acting on the drive gear **26x**.

Accordingly, positions of the developing rollers **26a** (that is, the non-rotating shafts **26a10**) do not vary in the developing devices **26** according to the present embodiment (or each time the support **26m** is attached to the developing case **26k**), and the developing roller **26a** (that is, the non-rotating shaft **26a10**) is accurately and stably positioned to the target position. As a result, the developing gap PG between the developing roller **26a** and the photoconductor drum **21** and

the doctor gap DG between the developing roller **26a** and the doctor blade **26c** are not likely to vary, and the image having the target image density and a stable image density difference is formed.

5 In particular, the developing roller **26a** and the photoconductor drum **21** in the present embodiment do not move in the same direction in the developing range. The developing roller **26a** moves in the opposite direction (counter direction) of the movement direction of the photoconductor drum **21** in the developing range. In this configuration, the variation 10 in the developing gap PG and the variation in the doctor gap DG are likely to cause an image density variation. Accordingly, the present disclosure is helpful.

15 Note that FIGS. 4 to 13B illustrate one end portion of the developing device **26** in the axial direction, but the other end portion of the developing device **26** in the axial direction may have the same configuration. Similar to the one end portion of the developing device **26** in the axial direction, the other end portion of the developing device **26** may include 20 the support **26m** and the gear holder **26n**.

25 The present inventors performed experiments to confirm variations in the developing gaps PG, the doctor gaps DG, and the image density differences when the support **26m** was attached to developing case **26k** to complete the developing device **26** according to the present embodiment in several times, and the support **126m** was attached to developing case **26k** to complete the developing device **126** illustrated as the comparative embodiment in FIGS. 8A and 8B in several times.

30 As a result, unacceptable variations in the developing gaps PG, the doctor gaps DG, and the image density differences occurred in the developing devices **126** according to the comparative embodiment. In contrast, all variations in the developing gaps PG, the doctor gaps DG, and the 35 image density differences in the developing devices **26** according to the present embodiment were acceptable levels.

The above-described experimental results confirmed the effect of the above-described embodiment.

Next, a first variation is described.

40 As illustrated in FIGS. 9A and 9B, the support **26m** in a first variation includes the base plate **26m1** as the main support having a hole **26m11** different from the hole illustrated in FIG. 7A. The hole **26m11** has a substantially same hole diameter as the shaft diameter of the non-rotating shaft **26a10**. The non-rotating shaft **26a10** penetrates the hole **26m11** and contacts the base plate **26m1**.

45 In addition, similar to the electrode as illustrated in FIGS. 7A and 7B, the electrode **26m2** as the conductor of the support **26m** has the D-shaped hole **26m20** as the fitting portion into which the D-cut portion **26a11** of the non-rotating shaft **26a10** is fitted.

50 In the support **26m** configured as described above, the hole **26m11** of the base plate **26m1** positions the non-rotating shaft **26a10** in addition to the D-shaped hole **26m20** of the electrode **26m2**, which is different from the support illustrated in FIGS. 7A and 7B. Accordingly, the above-described configuration can more accurately and stably position the developing roller **26a** than the configuration as illustrated in FIGS. 7A and 7B.

55 The present inventors performed experiments to confirm variations in the developing gaps PG, the doctor gaps DG, and the image density differences when the support **26m** was attached to developing case **26k** to complete the developing device **26** according to the first variation and the present embodiment including the support **26m** as illustrated in FIGS. 7A and 7B in several times. As a result, all variations 60 in the developing gaps PG, the doctor gaps DG, and the

image density differences in the developing devices **26** according to the first variation were smaller than those in the developing device **26** including the support **26m** as illustrated in FIGS. 7A and 7B.

In the first variation, the main-positioning portion of the electrode **26m2** with respect to the base plate **26m1** illustrated in FIG. 9B, that is, the boss inserted into the thermal caulking hole **26m23** may be removed. Removing the boss enables easily sliding the electrode **26m2** on the base plate **26m1** so that the non-rotating shaft **26a10** penetrates the electrode **26m2** and the base plate **26m1** even when the position of the shaft penetrating the hole **26m11** of the base plate **26m1** is relatively shifted from the position of the shaft penetrating the D-shaped hole **26m20**. In addition, designing a center line of the thermal caulking slot **26m24** serving as the sub-positioning portion of the electrode **26m2** so as to pass through the center of the D-shaped hole **26m20** can improve a positional accuracy of the D-cut portion **26a11** with respect to the non-rotating shaft **26a10**.

Next, a second variation is described.

As illustrated in FIGS. 10A and 10B, the support **26m** in a second variation includes the base plate **26m1** as the main support having a D-shaped hole **26m11** different from the holes illustrated in FIGS. 7A and 9A, and the D-cut portion **26a11** of the non-rotating shaft **26a10** is fitted into the D-shaped hole **26m11** as the fitting portion.

In addition, the electrode **26m2** as the conductor of the support **26m** has a circular hole **26m22** having a hole diameter substantially equal to or larger than the shaft diameter of the non-rotating shaft **26a10**, which is different from the electrodes illustrated in FIGS. 7B and 9B.

In the support **26m** configured as described above, the hole **26m11** of the base plate **26m1** positions the non-rotating shaft **26a10** without rotation. As a result, the developing roller **26a** is accurately and stably positioned.

A third variation is described.

As illustrated in FIG. 11A, the D-cut portion **26a11** formed on the non-rotating shaft **26a10** of the developing roller **26a** (that is, the magnets **26a1**) in the developing device **26** according to the third variation faces the photoconductor drum **21** in a cross section perpendicular to the axial direction of the non-rotating shaft **26a10**.

Specifically, in the cross section perpendicular to the axial direction, a flat portion of the fitting portion (that is the D-shaped hole **26m20** formed on the electrode **26m2** in FIG. 11A) of the support **26m** into which the D-cut portion **26a11** is fitted, that is, the flat portion facing the flat portion of the D-cut portion **26a11** is orthogonal to an imaginary line passing through the center axis of the photoconductor drum **21** and the center axis of the developing roller **26a**. In addition, the flat portion is disposed farther than the center axis of the developing roller **26a** from the photoconductor drum **21**.

Alternatively, as illustrated in FIG. 11B, the D-cut portion **26a11** formed on the non-rotating shaft **26a10** of the developing roller **26a** (that is, the magnets **26a1**) in the developing device **26** according to another embodiment of the third variation faces the idler gear **26y** disposed on the gear holder **26n** in a cross section perpendicular to the axial direction of the non-rotating shaft **26a10**.

Specifically, in the cross section perpendicular to the axial direction, a flat portion of the fitting portion (that is the D-shaped hole **26m20** formed on the electrode **26m2** in FIG. 11B) of the support **26m** into which the D-cut portion **26a11** is fitted, that is, the flat portion facing the flat portion of the D-cut portion **26a11** is orthogonal to an imaginary line passing through the center axis of the idler gear **26y** (that is,

the support shaft **26n5**) and the center axis of the developing roller **26a**. In addition, the flat portion is disposed farther than the center axis of the developing roller **26a** from the idler gear **26y**.

5 The configurations illustrated in FIGS. 11A and 11B enable easily setting the posture of the magnets **26a1** fixed not to rotate in the developing device **26** (that is, the angle of the magnets **26a1**) in the rotation direction of the developing roller **26a** with respect to the photoconductor drum **21** or the doctor blade **26c**. Specifically, as the developing device **26** is driven, the developing roller **26a** receives a pressure from the photoconductor drum **21** via the developer and receives a reaction force from the idler gear **26y**. The pressure and the reaction force at this time are forces pushing the D-cut portion **26a11** of the non-rotating shaft **26a10** to the flat portion of the D-shaped hole **26m20** of the electrode **26m2**. Accordingly, the flat portion of the D-shaped hole **26m20** of the electrode **26m2** accurately 10 determines the posture (that is, the angle) of the non-rotating shaft **26a10** in the rotation direction of the developing roller **26a**.

15 With reference to FIG. 12, a configuration regarding the D-cut portion **26a11** of the non-rotating shaft **26a10** in the third variation (or the second variation and the fourth variation described below) is described. Preferably, the D-cut portion **26a11** of the non-rotating shaft **26a10** is formed a range **W** in the axial direction from the middle of the hole **26m11** of the base plate **26m1** as the main support 20 to a tip of the non-rotating shaft **26a10** via the D-shaped hole **26m20** as the fitting portion of the electrode **26m2** as the conductor.

25 In the above-described configuration, at least a part of a hole of the base plate **26m1** into which the non-rotating shaft **26a10** is fitted is a cylindrical hole. In other words, at least a part of the hole **26m11** of the base plate **26m1** into which the D-cut portion **26a11** is fitted is the cylindrical hole. In addition, the D-cut portion **26a11** is fitted into the electrode **26m2** at a position at which the D-cut portion **26a11** on the 30 non-rotating shaft **26a10** starts to extend.

35 A cylindrical portion of the non-rotating shaft **26a10** has a higher dimensional accuracy than the D-cut portion **26a11**. Since the above-described configuration receives the cylindrical portion of the non-rotating shaft **26a10** on the base plate **26m1**, the above-described configuration can accurately 45 set the developing gap **PG**. Since the D-cut portion **26a11** is formed by performing secondary processing (milling processing) on the cylindrical portion of the non-rotating shaft **26a10**, in general, the D-cut portion **26a11** has a larger tolerance than the cylindrical portion, and the dimensional 50 accuracy of the D-cut portion **26a11** is inferior to that of the cylindrical portion.

55 If the D-cut portion **26a11** of the non-rotating shaft **26a10** penetrates an entire portion of the hole **26m11** of the base plate **26m1** in the axial direction, in other words, if the D-cut portion **26a11** of the non-rotating shaft **26a10** penetrates the hole **26m11** that is a cylindrical hole extending in the base plate **26m1** in the axial direction and is supported by the base plate **26m1**, in addition to the tolerance of the non-rotating 60 shaft **26a10** and the tolerance of the hole **26m11**, a clearance generated by the D-cut portion **26a11** increases the variation of the developing gap **PG** that is affected by pressures applied from the photoconductor drum **21** and the idler gear **26y**. Disposing the D-cut portion **26a11** of the non-rotating shaft **26a10** in the part of the hole **26m11** in the axial direction as illustrated in FIG. 12 can improve the disadvantage described above.

15

In the third variation, a plurality of magnetic poles generated by the magnets **26a1** are positioned to target positions in the rotational direction of the developing roller **26a** with respect to a D-cut surface (that is a flat surface) of the D-cut portion **26a11** as a reference. The D-cut surface (that is the flat surface) of the D-cut portion **26a11** is suitable for the reference because the D-cut surface is easily visible not only in the state of the developing roller **26a** alone but also in the state of being installed in the developing device **26** to confirm the positional relationship between the D-cut surface and the photoconductor drum **21** or the idler gear **26y**.

As a result, the above configurations reduce the variation of the postures of the magnets **26a1** (that is, the angles of the magnets **26a1**) in the rotation direction of the developing roller **26a** with respect to the photoconductor drum **21** or the doctor blade **26c** and enable forming images having stable and good image qualities.

A fourth variation is described.

As illustrated in FIG. 13A, the D-cut portion **26a11** formed on the non-rotating shaft **26a10** of the developing roller **26a** (that is, the magnets **26a1**) in the developing device **26** according to the fourth variation also faces the photoconductor drum **21** in the cross section perpendicular to the axial direction of the non-rotating shaft **26a10**. However, the D-cut portion **26a11** is disposed at a position rotated from the D-cut portion illustrated in FIG. 11A by approximately 180 degrees about the center axis of the non-rotating shaft **26a10**.

Specifically, in the cross section perpendicular to the axial direction, a flat portion of the fitting portion (that is the D-shaped hole **26m20** formed on the electrode **26m2** in FIG. 13A) of the support **26m** into which the D-cut portion **26a11** is fitted, that is, the flat portion facing the flat portion of the D-cut portion **26a11** is orthogonal to an imaginary line passing through the center axis of the photoconductor drum **21** and the center axis of the developing roller **26a**. In addition, the flat portion is disposed nearer to the photoconductor drum **21** than the center axis of the developing roller **26a**.

Alternatively, as illustrated in FIG. 13B, the D-cut portion **26a11** formed on the non-rotating shaft **26a10** of the developing roller **26a** (that is, the magnets **26a1**) in the developing device **26** according to another embodiment of the fourth variation also faces the idler gear **26y** disposed on the gear holder **26n** in a cross section perpendicular to the axial direction of the non-rotating shaft **26a10**. However, the D-cut portion **26a11** is disposed at a position rotated from the D-cut portion illustrated in FIG. 11B by approximately 180 degrees about the center axis of the non-rotating shaft **26a10**.

Specifically, in the cross section perpendicular to the axial direction, a flat portion of the fitting portion (that is the D-shaped hole **26m20** formed on the electrode **26m2** in FIG. 13B) of the support **26m** into which the D-cut portion **26a11** is fitted, that is, the flat portion facing the flat portion of the D-cut portion **26a11** is orthogonal to an imaginary line passing through the center axis of the idler gear **26y** (that is, the support shaft **26n5**) and the center axis of the developing roller **26a**. In addition, the flat portion is disposed nearer to the idler gear **26y** than the center axis of the developing roller **26a**.

The configurations illustrated in FIGS. 13A and 13B enable easily setting the posture of the magnets **26a1** fixed not to rotate in the developing device **26** (that is, the angle of the magnets **26a1**) in the rotation direction of the developing roller **26a** with respect to the photoconductor drum **21** or the doctor blade **26c**. Specifically, the plurality of mag-

16

netic poles generated by the magnets **26a1** are positioned to the target positions in the rotational direction of the developing roller **26a** with respect to the D-cut surface (that is the flat surface) of the D-cut portion **26a11** as the reference. The D-cut surface (that is the flat surface) of the D-cut portion **26a11** is suitable for the reference because the D-cut surface is easily visible not only in the state of the developing roller **26a** alone but also in the state of being installed in the developing device **26** to confirm the positional relationship between the D-cut surface and the photoconductor drum **21** or the idler gear **26y**.

As a result, the above configurations reduce the variation of the postures of the magnets **26a1** (that is, the angles of the magnets **26a1**) in the rotation direction of the developing roller **26a** with respect to the photoconductor drum **21** or the doctor blade **26c** and enable forming images having stable and good image qualities.

As described above, the developing device **26** includes the developing roller **26a**. The developing roller **26a** includes the rotatable sleeve **26a2** and the magnets **26a1** as the magnetic field generator irrotationally disposed in the sleeve **26a2**. In addition, the developing device **26** includes the developing case **26k** to store the developer inside and rotatably support the hollow shaft **26a20** formed at the axial ends of the sleeve **26a2**. In addition, the non-rotating shafts **26a10** are attached to both ends of the magnets **26a1**. The non-rotating shaft **26a10** penetrates through the hollow shaft **26a20** and projects outward. The developing device **26** includes the support **26m** having the hole **26m20** (the fitting portion). The non-rotating shaft **26a10** of the magnets **26a1** is fitted into the hole **26m20**. The support **26m** is supported on the developing case **26k** using the hole **26m20** as the main-positioning portion.

As a result, the developing roller **26a** is accurately and stably positioned.

In the present embodiment, the process cartridge **20** does not include the developing device **26**, and the developing device **26** is a unit that can be independently installed in and removed from the body of the image forming apparatus **1**. In contrast, the developing device **26** may be one of the constituent members of the process cartridge **20**, and the process cartridge **20** may be configured to be integrally installed in and removed from the body of the image forming apparatus **1**.

In such a configuration, similar effects to those of the above-described embodiment and variations are also attained.

It is to be noted that the term “process cartridge” used in the present disclosure means a removable unit including an image bearer and at least one of a charging device to charge the image bearer, a developing device to develop latent images on the image bearer, and a cleaning device to clean the image bearer that are united together and is designed to be removably installed as a united part in the body of the image forming apparatus.

In the present embodiment according to the present disclosure, the developing device **26** includes two conveying screws **26b1** and **26b2** as the conveyors horizontally arranged in parallel and the doctor blade **26c** disposed above the developing roller **26a**. The configuration of the developing device to which the present disclosure is applied is not limited to the above-described configurations. The present disclosure may be applied to other developing devices such as a developing device including two conveyors obliquely arranged, a developing device including two conveyors arranged in parallel in the vertical direction, a developing device including three or more conveyors arranged, a devel-

oping device including the doctor blade disposed below the developing roller, or a developing device in which the developing roller rotates in the same direction as the photoconductor drum rotates in the developing range.

Applying the present disclosure to the above developing devices can provide effects similar to the effects of the above-described embodiments and variations.

The above-described embodiments are illustrative and do not limit the present disclosure. Thus, numerous additional modifications and variations are possible in light of the above teachings. It is therefore to be understood that within the scope of the present disclosure, the present disclosure may be practiced otherwise than as specifically described herein. The number, position, and shape of the components described above are not limited to those embodiments described above. Desirable number, position, and shape can be determined to perform the present disclosure.

What is claimed is:

1. A developing device, comprising:
a developing roller including:

a sleeve that is rotatable, the sleeve including a hollow shaft at an axial end of the sleeve; and
a magnetic field generator that is irrotationally disposed inside the sleeve, the magnetic field generator including a non-rotating shaft at an axial end of the magnetic field generator, and the non-rotating shaft penetrating through the hollow shaft and projecting outward;

a developing case to store developer and rotatably support the hollow shaft; and

a support including a fitting portion into which the non-rotating shaft of the magnetic field generator is irrotationally fitted, the support being supported on the developing case using the fitting portion as a main-positioning portion, wherein

the support further includes,

a main support of a non-conductive material, and
a conductor of a conductive material, the conductor is fixed on the main support, and the conductor to apply a developing bias to the developing roller via the non-rotating shaft.

2. The developing device according to claim 1, further comprising:

a drive gear disposed on the hollow shaft, the drive gear to rotate together with the sleeve;
a gear meshing the drive gear; and
a gear holder supported on the developing case together with the support, the gear holder to rotatably hold the gear.

3. The developing device according to claim 1, wherein a part of the non-rotating shaft includes a flat surface portion which extends parallel to an axis of the non-rotating shaft,

the main support has a hole having a hole diameter larger than a shaft diameter of the non-rotating shaft and being penetrated by the non-rotating shaft that does not contact the main support, and

the conductor has the fitting portion into which the flat surface portion of the non-rotating shaft is fitted.

4. The developing device according to claim 3, wherein the flat surface portion is disposed at a position rotated from a position at which the flat surface portion faces a photoconductor drum to be faced by the developing roller by 180 degrees about a center axis of the non-rotating shaft in a cross section of the flat surface portion orthogonal to an axial direction of the non-rotating shaft.

5. The developing device according to claim 3, further comprising:

a drive gear disposed on the hollow shaft, the drive gear to rotate together with the sleeve; and
a gear meshing the drive gear, wherein
the flat surface portion is disposed at a position rotated from a position at which the flat surface portion faces the gear by 180 degrees about a center axis of the non-rotating shaft in a cross section of the flat surface portion orthogonal to an axial direction of the non-rotating shaft.

6. The developing device according to claim 3, wherein the flat surface portion faces a photoconductor drum to be faced by the developing roller in a cross section of the flat surface portion orthogonal to an axial direction of the non-rotating shaft.

7. The developing device according to claim 3, further comprising:

a drive gear disposed on the hollow shaft, the drive gear to rotate together with the sleeve; and
a gear meshing the drive gear, wherein
the flat surface portion faces the gear that in a cross section of the flat surface portion orthogonal to an axial direction of the non-rotating shaft.

8. The developing device according to claim 3, wherein a part of the non-rotating shaft is a D-cut portion including the flat surface portion.

9. The developing device according to claim 1, wherein a part of the non-rotating shaft includes a flat surface portion,
the main support has a hole having a hole diameter substantially equal to a shaft diameter of the non-rotating shaft and being penetrated by the non-rotating shaft that contacts the main support, and
the conductor has the fitting portion into which the flat surface portion of the non-rotating shaft is fitted.

10. The developing device according to claim 9, wherein the flat surface portion is in a range on the non-rotating shaft from a middle of the hole of the main support to a tip of the non-rotating shaft via the fitting portion of the conductor.

11. The developing device according to claim 1, wherein a part of the non-rotating shaft is a flat surface portion, and the main support has the fitting portion into which the flat surface portion of the non-rotating shaft is fitted.

12. The developing device according to claim 11, wherein the fitting portion includes a hole of the main support.

13. The developing device according to claim 12, wherein a part of the non-rotating shaft is a D-cut portion including the flat surface portion, and the fitting portion includes a D-shaped hole into which the D-cut portion of the shaft is fitted.

14. The developing device according to claim 1, further comprising:

a bearing disposed on the hollow shaft, the bearing to contact a photoconductor drum to define a gap between the photoconductor drum and the developing roller.

15. An image forming apparatus, comprising:
the developing device according to claim 1.

16. A developing device, comprising:
a developing roller including:

a sleeve that is rotatable, the sleeve including a hollow shaft at an axial end of the sleeve; and
a magnetic field generator that is irrotationally disposed inside the sleeve, the magnetic field generator including a non-rotating shaft at an axial end of the

19

magnetic field generator, and the non-rotating shaft penetrating through the hollow shaft and projecting outward; and

a support including a fitting portion into which the non-rotating shaft of the magnetic field generator is irrotationally fitted, wherein

the support further includes

a main support of a non-conductive material, and

a conductor of a conductive material, the conductor is fixed on the main support, and the conductor to apply a developing bias to the developing roller via the non-rotating shaft,

a part of the non-rotating shaft includes a flat surface portion which extends parallel to an axis of the non-rotating shaft,

the main support has a hole having a hole diameter larger than a shaft diameter of the non-rotating shaft and being penetrated by the non-rotating shaft that does not contact the main support, and

the conductor has the fitting portion into which the flat surface portion of the non-rotating shaft is fitted.

17. A developing device, comprising:

a developing roller including:

a sleeve that is rotatable, the sleeve including a hollow shaft at an axial end of the sleeve; and

a magnetic field generator that is irrationally disposed inside the sleeve, the magnetic field generator

including a non-rotating shaft at an axial end of the magnetic field generator, and the non-rotating shaft penetrating through the hollow shaft and projecting outward; and

a support including a fitting portion into which the non-rotating shaft of the magnetic field generator is irrotationally fitted, wherein

the support further includes

a main support of a non-conductive material, and

a conductor of a conductive material, the conductor is fixed on the main support, and the conductor to apply a developing bias to the developing roller via the non-rotating shaft,

a part of the non-rotating shaft includes a flat surface portion,

the main support has a hole having a hole diameter substantially equal to a shaft diameter of the non-rotating shaft and being penetrated by the non-rotating shaft that contacts the main support,

the conductor has the fitting portion into which the flat surface portion of the non-rotating shaft is fitted, and the flat surface portion is in a range on the non-rotating shaft from a middle of the hole of the main support to a tip of the non-rotating shaft via the fitting portion of the conductor.
